UNITED STATES PATENT OFFICE.

WALDEMAR DYRSSEN, OF NEW YORK, N. Y.

REGENERATOR.

Application filed January 27, 1922. Serial No. 532,192.

To all whom it may concern:

Be it known that I, WALDEMAR DYRSSEN, a citizen of the United States, and resident of the city, county, and State of New York, have invented certain new and useful Improvements in Regenerators, of which the following is a specification.

This invention relates to improvements in metallurgical furnaces and particularly to 10 the arrangement of the regenerative chambers therefor whereby means are provided for trapping or catching the greater part of the dust particles carried in suspension by the exhaust gases from an open hearth furnace.

One embodiment of the invention is illustrated in the accompanying drawings in which

Fig. 1 is a horizontal section through an 20 open hearth furnace showing the regenerators in top plan;

Fig. 2 is a similar view in horizontal section taken on a lower plane showing the regenerators, the slag pocket and the dust 25 separating passage. In this view the checker-work is omitted from the regenerator on the right side to show the supporting girders therefor;

Fig. 3 is a vertical section through the 30 dust separating passage, the slag pocket and the up-take at one end of the furnace the section being taken on the line 3—3 of Fig. 2;

Fig. 4 is a vertical section through one 35 end of the furnace on the line 4—4 of Fig. 1;

Fig. 5 is a section on the line 5—5 of Fig. 2 showing the regenerators and the dust separating passage.

Referring to the embodiment illustrated, 40 the furnace 10 comprises the usual hearth 12, roof 14 and a combustion or mixing chamber 16 which is connected by suitable up-takes 18 with a slag pocket 20 formed by a bridge wall 21 at one side. A vertical wall 45 22 between the two up-takes 18 carries a pipe 24 through which fuel is introduced. The fuel used is preferably pulverized coal, tar or by-product coke oven gas, oil or any other fuel which does not require preheating. 50 Heretofore furnaces using producer gas and other gases of low thermal value have preheated the gas in special regenerative chambers so as to promote their efficient combustion within the furnace.

55 When using fuels such as above mentioned which do not require preheating, it is un-

necessary to utilize such a great area for the regenerative chambers. Heretofore it has been almost universal practice to use regenerators for both gas and air, but the present day practice leans toward the use of fuels not requiring preheating. One of the difficulties with such fuels, however, is that they introduce a considerable quantity of dust into the furnace and this is particularly true 65 when using pulverized coal.

My invention aims to provide means whereby this dust can be effectively separated from the exhaust gases so that it will not enter the regenerators and clog up the 70 checker-work therein. In order to use pulverized fuel for existing furnaces it is only necessary to provide a suitable fuel inlet and alter the regenerators so that the chambers formerly used for preheating the 75 fuel can be used for preheating the air. The total volume of such former regenerators is greater than that required to preheat the air alone. Therefore, the space in such regenerators can readily be utilized for trapping or catching the dust carried in suspension by the exhaust gas.

In Fig. 2 the regenerators 26 and 28 are separated by a central passage 30, the opposed walls 32 and 34 which are provided 85 with ports 36 and 38 communicating with the regenerators 26 and 28 respectively. The dust separating chamber is connected with the slag pocket 20 by a port 40 having inclined top and bottom walls as shown in 90 Fig. 3. At one end the dust separating chamber 30 is closed by a thin wall 42 built in a doorway 44 which is adapted to be removed to permit the cleaning out of the accumulated dust in the passage 30. 95

In operation the pulverized fuel entering through the burner 24 meets the heated air which has passed through the regenerators, passage 30, port 40 and up-takes 18 and combustion takes place in the mixing chamber 16 and the exhaust gases are carried out through the slag pocket, separating chamber and regenerator at the opposite end, not shown. When the furnace is reversed exhaust gases pass down through the up-takes 18, the larger particles of slag being caught in the slag pocket 20, the gases flowing through a port 40 and being directed downwardly by the inclined walls of said port 40 so that the greater volume of dust carried in suspension falls to the bottom of the 105 passage 30. The dust free gas then flows 110

through the ports 36 and 38 to the regenerators 26 and 28 giving up the greater part of the heat thereto, the spent gases flowing through suitable flues 27 and 29 to the stack, not shown. With this arrangement it is apparent that the exhaust gases flowing through the passage 30, which is located between the opposed walls 32 and 34 of the regenerators, give up the greater part of their heat before they contact with any regenerator walls which are exposed to atmosphere. This results in a considerable conservation of heat energy which is not possible in structures heretofore built in which the exhaust gases flow in contact with walls having a considerable area exposed to atmosphere.

From the foregoing it will be seen that my improved structure effectively separates the dust from the exhaust gases of an open hearth furnace and that the greater part of the heat from these gases is utilized to heat the regenerators before the gases contact with walls which are exposed to and therefore cooled by atmosphere. It is also apparent that existing furnaces can be altered by decreasing the area of both the air and gas regenerators formerly used and yet have a combined area available for air regenerators and a dust separating chamber.

While I have described with great particularity the details of the embodiment shown, it is not to be construed that I am limited thereto, as changes in arrangement and modifications may be made by those skilled in the art without departing from the invention as defined in the appended claims.

What I claim is:

1. A regenerative metallurgical furnace

adapted to heat the air but not the fuel for combustion, having an uptake at the lower end of which is a slag pocket, and having a pair of regenerators alongside of each other with a dust separating passage between them, and having a bridge wall at the side of the slag pocket toward said dust separating passage.

2. A regenerative metallurgical furnace adapted to heat the air but not the fuel for combustion, having an uptake at the lower end of which is a slag pocket, and having a pair of regenerators alongside of each other with a dust separating passage between them, and a passageway between the slag pocket and the dust separating passage leading downward to the latter.

3. A regenerative metallurgical furnace adapted to heat the air but not the fuel for combustion, having an uptake at the lower end of which is a slag pocket, and having a pair of regenerators alongside of each other with a dust separating passage between them, and a passageway between the slag pocket and the dust separating passage leading downward to the latter, the side walls of said dust separating passage having ports near the top for the admission of the gases to the regenerators after the removal of the dust in said passage.

4. In a metallurgical furnace a pair of regenerators for heating the air, the opposed walls of said regenerators forming a central passage extending the full length and full height of the regenerators, and ports in said walls communicating with said regenerators.

In witness whereof, I have hereunto signed my name.

WALDEMAR DYRSSEN.
